UNITED STATES PATENT OFFICE.

GEORGE N. MAS AND NELLIE ZAKI, OF LYNCHBURG, VIRGINIA.

INVALID BED.

Application filed May 10, 1924. Serial No. 712,250.

This invention relates to certain improvements in invalid beds of the type wherein an opening is provided in the mattress to permit the patient to perform the necessary evacuations where it is impossible to leave the bed, due either to temporary illness or to a paralyzed or bed-ridden condition.

One of the chief objections to mattresses of this type, is that they soon become mashed down around the opening, forming a hollow spot to the discomfort of the patient and spoiling the matress for general use.

A further disadvantage is that the matress, around the opening also becomes soiled and unsanitary in a very short time necessitating a replacement of the whole matress.

Another objection to the usual construction of this character is that no special arrangement is provided to obtain a sanitary connection between the receiving vessel and the matress attachment and still retain the resiliency of the bed or matress, when the vessel is supported upon the floor.

The object of this invention is to provide a bed construction comprising a matress and cooperating parts of the type indicated, involving certain improved details eliminating the above enumerated objectional features, thus adding to the convenience and comfort of the patient, and providing a simple, inexpensive and sanitary device and one adapted for use in connection with beds of different heights.

The preferred embodiment of the invention is illustrated in the accompanying drawings in which,

Figure 1 is a view partly in section and partly in elevation of the various parts completely assembled;

Figure 2 is an enlarged fragmentary plan view;

Figure 3 is an enlarged view partly in section and partly in elevation of the resilient supporting ring for the matress at the opening;

Figure 4 is a modification; and

Figure 5 is a view of the matress section to be inserted in the opening when the matress is in every day use.

Referring to the drawings in detail, the matress 1 is supported upon the usual type of bed springs 2, as shown, or in place of a coil spring construction a woven spring may be used as the case may be.

In approximately the center of the mat-

tress a substantially circular opening 3 is formed and the ticking or other covering 4 of the matress is continued around the edges of this opening in an obvious manner to retain the filling.

Positioned around the periphery of the opening 3 and enclosed by the covering 4 is an annular telescoping member 5 of any suitable material, but preferably metal, for the purpose of sustaining the matress at this particular point. It is necessary of course to have this member more or less resilient and this is accomplished in the preferred arrangement by forming the member 5 of two telescoping members 6 and 7, the member 6 being substantially V-shaped in cross section. Supporting the member 6 upon the member 7 is a series of springs 8, the lower ends of said spring seating in recesses 9 formed around the upper edge of the member 7, and the upper ends of the springs being maintained in proper position by pins or the like 10, depending from the member 6. To prevent the metal of this telescoping member from coming in direct contact with the matress covering 4, the upper annular edge of the member 6 and the lower annular edge of the member 7 are preferably covered with rubber or the like, as shown at 11 and 12.

Adapted to be suspended within the opening 3 is a funnel-shaped member 13, made of any preferred substantially rigid material, having an upper annular flange 14 for supporting the same upon the upper surface of the matress. Overlying the upper portion of the funnel 13 and extending partially into the same is a rubber mat or shield 15. The shield 15 is substantially circular in shape except for a tab or extension 16 to be used when desired in an obvious manner during the operation of the device. The under face of the mat 15 and the top covering 3 of the matress are provided with complementary snap fastenings 17, all of which is clearly shown in Figures 1 and 2.

The lower end of the funnel 13 is provided with a neck 18 having telescoping engagement with a screw coupling member 19 which latter is adapted to be threaded into the neck of a receiving vessel 20. With this arrangement there is a direct and substantially closed connection between the bed opening and receiving vessel and by reason of the telescoping arrangement of the parts

18 and 19 this connection is not disturbed by any rising or sinking of the mattress or springs and the device as a whole will be equally well adapted to beds of different heights. Furthermore any transverse movement of the bed will not interfere or disarrange this connection. However, if desired, in order to maintain the bed in any predetermined position the legs of the same may be provided with anchoring floor plates 22. The vessel 20 is also provided with an externally threaded neck portion 23 to receive a closure, 24, when removed from the bed.

15 Figure 4 illustrates a modified form of support for the mattress around the opening 3 comprising a coil spring 25. Positioned between the top and bottom edges of the spring 25 and the mattress covering 4 are flat annular members 26 and 27 respectively, to prevent the edges of the spring 25 from cutting through the covering 4.

20 When the device hereinbefore described is not in use the opening 3 in the mattress may be closed by a mattress section 28.

25 Having described the invention what is claimed is:

1. In an invalid bed, the combination with a mattress provided with an opening therethrough, of an annular telescoping resilient member for supporting the mattress at the edge of said opening, a tubular member positioned in said opening, a receiving

vessel and a telescoping connection between said tubular member and receiving vessel.

2. In an invalid bed, the combination with a mattress provided with an opening therethrough, of an annular member comprising telescoping parts for supporting the mattress at the edge of said opening and resilient means for normally extending said telescoping parts.

3. In an invalid bed, the combination with a mattress provided with an opening therethrough, of an annular member comprising telescoping parts for supporting the mattress at the edge of said opening and springs for normally extending said telescoping parts and means for anchoring said springs between the telescoping parts.

4. In an invalid bed, the combination with a mattress provided with an opening therethrough, of an annular member comprising telescoping parts for supporting the mattress at the edge of said opening, protective coverings applied to the upper and lower edges of said annular mattress supporting member, and springs for normally extending said telescoping parts and means for anchoring said springs between the telescoping parts.

In testimony whereof we affix our signatures.

GEORGE N. MAS.
NELLIE ZAKI.
